GRID FOR COOK-OUT GRILL

Richard Kates, Park Lane, Madison, N.J.

Filed Aug. 18, 1958, Ser. No. 52,239

Term of patent 14 years

(Cl. D81—25)

*Fig. 4**Fig. 5*Figure 1 is a top plan view;

Figure 2 is a side elevation thereof;

Figure 3 is a front elevation thereof;

Figure 4 is an enlarged bottom plan view of the portion bounded by the dot and dash line 4-4 of Figure 1; and

Figure 5 is a transverse vertical sectional view on the plane of the line 5-5 of Figure 1.

I claim:

The ornamental design for a grid for cook-out grill, as shown.
